United States Patent [19]

Iino et al.

[11] **Patent Number:** Des. 332,780[45] **Date of Patent:** ** Jan. 26, 1993[54] **ELECTRONIC COMPUTER**[75] Inventors: Masaaki Iino; Masaharu Mukasa,
both of Yokohama, Japan[73] Assignee: Kabushiki Kaisha Toshiba,
Kanagawa, Japan

[**] Term: 14 Years

[21] Appl. No.: 446,706

[22] Filed: Dec. 6, 1989

[30] **Foreign Application Priority Data**

Jun. 9, 1989 [JP] Japan 1-21101
